2 SHEETS—SHEET 2.

UNITED STATES PATENT OFFICE.

WILLIAM E. BUTE, OF STANHOPE, IOWA.

KNOCKDOWN HOG-CRATE.

1,381,892.

Specification of Letters Patent. Patented June 14, 1921.

Application filed July 8, 1919. Serial No. 309,393.

To all whom it may concern:

Be it known that I, WILLIAM E. BUTE, a citizen of the United States, and resident of Stanhope, in the county of Hamilton and State of Iowa, have invented a certain new and useful Knockdown Hog-Crate, of which the following is a specification.

The object of my invention is to provide a knock-down hog crate of simple, durable 10 and inexpensive construction.

A further object is to provide a crate having end closure members for permitting access into said crate, and means for locking said closure members.

15 Still a further object is to provide a knock-down crate comprising a base, wall members, a top and means for removing the base so as to permit the collapsing of the remaining portion of said crate.

20 Still a further object is to provide a wheel mounted base, having a detachable crate mounted thereon, and means so that the device can readily be moved from place to place, and when the crate is detached from 25 said base the base can be used as a cart or the like.

Still a further object is to provide a crate detachably mounted on wheels, where after detaching said crate from said wheels said 30 crate may be collapsed.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side view of my device.

40 Fig. 2 shows a top view of my device.

Fig. 3 is a central sectional view taken on the line 3—3 of Fig. 2.

Fig. 4 shows a side elevation of the truck after the crate has been detached therefrom.

45 Fig. 5 shows a view of the device when collapsed.

Fig. 6 shows an end view showing the door members and the closing means for the doors; and

50 Fig. 7 shows a view taken on the line 7—7 of Fig. 2.

In the accompanying drawings I have used the reference numeral 10 to indicate generally a base or platform. The base 10 is mounted on caster wheels 11. The base 10 comprises a pair of longitudinal angle

irons 12, and the caster wheels 11 are secured to the angle irons 12 by means of the bolts 13.

Resting upon one side of the angle irons 60 is a floor 14, which is comprised of a series of boards. Resting upon the boards are strap members 15, which are bolted through the boards and the lower portions of the angle irons by means of the bolts 16. The 65 strap members 15 extend over all of the floor boards and thereby keep the floor boards upon the lower portion of the angle irons.

The angle irons have a plurality of openings 17 in their ends, which are adapted to 70 receive upright posts 18. The posts 18 have screw-threaded portions 19 and 20 thereon, which are adapted to receive nuts 21 and 22. Sleeves 23 are placed upon the upright posts 18. Between the sleeves 23 on opposite sides 75 of the device are wall members 24 which have their ends adapted to straddle the posts 18. The ends of each wall member 24 are arranged so that one end comes on the inside of one of the upright posts and the other 80 end comes on the outside of another of said posts.

Rods 25 are fastened at their ends to the upright posts 18. The members 24 and 25 form side wall members for the crate.

Pivoted on the upright posts 18 are end door members 26. The door members 26 have secured thereto rods 27 which are adapted to wrap around the posts 18, thereby forming a hinge member.

Pivoted on one of the posts 18 at each end of the crate are hook members 28 which have elongated slots 29 therein. Fixed on the door 26 are projections 30 having openings therein. The members 28 having the 95 slots 29 therein are adapted to pass over the projections 30, and a rod 31 is placed into the openings 30, thereby locking the door member 26 against movement.

A bar 32 which has its ends fastened 100 around the posts 18 and resting upon the lower portion of the angle irons 12, is designed to act as a stop against the inward movement of the door member 26.

Fixed on the posts 18 at their upper ends 105 are cross rods 33 having inwardly extending hook portions 34. A rod 35 is adapted to have its ends received in the hooks 34 of the cross rods 33, and acts as a top for the crate.

Bolted to the angle irons 12 are vertical, 110 upwardly extending angle irons 36 and 37. The vertical angle irons 36 and 37 are also

fixed to the member 24 by means of rivets 38. A cross member 39 is secured to the upper ends of the angle irons 36 and 37 by means of the wing bolts 40. At the forward end of the crate and secured to the angle irons 12 are the extensions 41, which have openings therein which are adapted to receive the handles or tongues 42.

In the practical operation of my device 10 when the crate is substantially fixed as is shown in Fig. 1, the end door members 26 are opened by the removing of the upright rod 31 from the lugs 30 and swinging the members 28 a quarter of a turn so that the door may be opened away from the crate. It is then very easy to place the animal in the crate, as it is only necessary to force the animal to walk forward into the crate.

When it is desired to remove the animal 20 from the crate the door on the opposite end is opened and the animal again compelled to move forward.

It will be noted that with my improved construction the animal always enters and 25 leaves the crate by moving forward.

When it is desired to detach the crate from the wheels the nuts 22 are unscrewed the members 36 and 37 are unbolted and the entire crate is then raised away from the 30 platform and the wheels. When the crate is removed a truck comprising a platform and caster wheels, having a tongue at the forward end, will be left, substantially as is shown in Fig. 4 of the drawings. In this 35 way when the crate portion is removed the remaining portion may be used for carting freight from place to place.

When it is desired to remove any of the 40 boards from the floor of the platform, for repairing or replacing it, the bolts 16 are unscrewed and the straps 15 are taken off the top of the boards, thereby permitting the board floor to be taken apart.

It will be noted that when the crate portion 45 is separated from the wheel-mounted platform, substantially four wall members and the top member will be left. The walls being pivoted to the upright posts 18 can then be moved so that the side walls will 50 come together and the end and side walls will then form a parallelogram, substantially as is shown in Fig. 5 of the drawings.

If it is desired to collapse the entire crate 55 and platform the bolts 16 are removed so as to permit the floor boards to be taken from the platform and then the crate and walls can be collapsed in the same manner as if the crate had been removed from the platform.

It will be seen that before the crate could 60 be collapsed the cross bar 39, which is bolted to the upright angle irons 36 and 37, would have to be detached at one end. This is done by removing one of the wing bolts 40 and

using the other as an axis, and the cross member 39 could then be thrown around until it would stand adjacent to one of the upright angle irons. It will be seen that the crate can readily be moved from place to place, and that the top of the crate may be 70 collapsed in order to make it more compact. The crate when collapsed may be placed upon the platform, which will enable the crate to be easily moved from place to place.

Some changes may be made in the construction and arrangement of the various parts of my device without departing from the essential features and purposes of my invention, and it is my intention to cover 80 by my claims any modified forms of structure or use of mechanical equivalents which may be reasonably included within their scope.

I claim as my invention:

1. In a knock-down crate, a wheel mounted base comprising laterally spaced, longitudinally arranged, angle irons, caster wheels for supporting said angle irons, a floor resting on said angle irons, upright posts detachably mounted on said angle irons, side frame members on opposite sides of the 90 crate, pivotally supported on said posts, doors pivotally supported on the posts at each end of the crate, cross members pivoted to the upright posts at each end of the crate, a central longitudinal member, pivoted at its ends to the respective cross members.

2. In a knock-down crate, a wheel mounted base comprising laterally spaced, longitudinally arranged, angle irons, caster wheels for supporting said angle irons, a floor resting on said angle irons, upright posts detachably mounted on said angle irons, side frame members on opposite sides 100 of the crate, pivotally supported on said posts, doors pivotally supported on the posts at the opposite ends of the crate, means for locking the doors in closed positions, cross members pivoted to the upright posts at each 110 end of the crate, a central longitudinal member, pivoted at its ends to the respective cross members, upright members secured to said angle irons near the middle of the crate, and a cross member for connecting the upper ends of the said last described upright members.

3. In a collapsible hog crate, a base, side frame members pivotally supported on opposite sides of the crate, doors pivotally 120 supported on the posts at the opposite ends of the crate, means for locking the doors in closed positions, cross members pivoted to the upright posts at each end of the crate and a central longitudinal member, pivoted 125 at its ends to the respective cross members.

Des Moines, Iowa, April 23, 1919.

WILLIAM E. BUTE.
